UNITED STATES PATENT OFFICE.

WILLIAM R. HART, OF PHILADELPHIA, PENNSYLVANIA, ASSIGNOR TO GEORGE A. REACH, OF PHILADELPHIA, PENNSYLVANIA.

PLAYING-BALL COVER.

Application filed November 12, 1925. Serial No. 68,567.

My present invention relates to a playing ball covering, such playing balls being of the football, soccer ball, volley ball, Rugby football, basketball, striking bag, play-ground ball, water pool balls, and the like.

The principal object of the invention is the provision of a covering for such a ball which will make a lighter ball than is at present in use, which will add to its elasticity or 10 rebound quality, which will be of a superior strength, and which will allow the ball to hold and retain its shape for a much longer period of time. Obviously, the balls made of the covering of this invention may be inflated, stuffed, wrapped, or otherwise filled, 15 as desired.

To this end my invention consists in the provision of two layers of leather with an intermediate layer of fabric, located between 20 the two leather plies, and cementing, fastening, or adhering the said fabric in place.

I have illustrated in the accompanying drawing, a preferred form of the invention, although obviously I do not wish to be 25 limited to the exact form or material shown.

In the drawings:—

Figure 1 is a sectional elevation of a football made of the covering of this invention.

Fig. 2 is an enlarged detail of one sector 30 showing the structure more in detail.

Referring now with particularity to the drawing, I have shown the outside leather plies at 1, and an inside leather plies at 2, with an intermediate layer of fabric at 3, suitably secured therein by any desired manner. I have found that these three laminations 35 may be readily cemented together.

As shown in the illustration the layer 1

forms the outer covering of the football, and the layer 2 the inner layer lying next to the 40 bladder in balls in which a bladder is used.

The layer 3 is preferably of fabric although it may take the form of a rubberized fabric.

Sheets of this composite material may be 45 cut to any desired form and then put together to form the ball structure, as is the usual case, the composite material being handled as a single sheet.

The composite covering thus described 50 will not chafe the bladder, where bladders are used, the layers will not creep upon each other, and to all intents and purposes it forms a unitary structure which has qualities not found in a single or several plies of 55 leather, or even leather and fabric without the arrangement of leather and fabric being in the form shown.

In the claims where I have described the object as a playing ball, it is to be understood 60 that this also covers such an article as a striking bag, the word "ball" being used for lack of a better term.

Having thus described my invention, what I claim is:—

1. A covering for a playing ball comprising a plurality of plies of leather, and an intermediate sheet of fabric held therebetween.

2. A covering for a playing ball comprising two plies of leather, and an intermediate sheet of fabric cemented on each of its sides to the over- and under-lying leather plies.

In testimony whereof, I affix my signature.

WILLIAM R. HART.
